UNITED STATES PATENT OFFICE

MURRAY C. TUNISON, OF FULLERTON, CALIFORNIA

DESIGN FOR AN AIRPLANE

Application filed December 28, 1928. Serial No. 29,426. Term of patent 7 years.

To all whom it may concern:

Be it known that I, MURRAY C. TUNISON, a citizen of the United States, now residing at Fullerton, in the county of Orange and State of California, have invented a new, original, and ornamental Design for Airplane, of which the following is a specification, reference being had to the accompanying drawing, forming part thereof.

Fig. 1 is a side elevation of the airplane showing my new design.

Fig. 2 is a top plan view of the same.

Fig. 3 is a front elevation of the same in flying position.

Fig. 4 is a front elevation of the same resting on the ground.

I claim:

The ornamental design for an airplane substantially as shown.

MURRAY C. TUNISON.
